UNITED STATES PATENT OFFICE.

FRANK. G. DODGE, OF WISCOY, AND DANIEL C. STARKS, OF WARSAW, NEW YORK; SAID DODGE ASSIGNOR TO SAID STARKS.

LAND-ROLLER.

SPECIFICATION forming part of Letters Patent No. 450,006, dated April 7, 1891.

Application filed January 9, 1891. Serial No. 377,273. (No model.)

To all whom it may concern:

Be it known that we, FRANK. G. DODGE, of Wiscoy, in the county of Allegany, and DANIEL C. STARKS, of Warsaw, in the county of Wyoming, and State of New York, have invented a certain new and useful Improvement 5 in Land-Rollers; and we do hereby declare that the following is a full, clear, and exact description of the same, reference being had to the drawings accompanying this specification.

Our improvement relates to that class in which the roller is made in two sections, one standing in advance of the other, the two making the length of an ordinary roller.

15 The invention consists in the jointed connection between the sections, and also in certain devices by which the rollers may be locked to follow in direct line, as hereinafter described and claimed.

20 In the drawings, Figure 1 is a plan view of the machine. Fig. 2 is a side elevation. Fig. 3 is an enlarged plan view of the connecting devices between the rollers. Fig. 4 is a vertical section of the same.

25 A A' indicate the two short rollers, standing one in advance of the other and out of line, as in other rollers of the class. The inner ends lap past each other, so as to leave no break in the surface over which they pass.

30 B B' are frames to the rollers, extending over the tops of the same longitudinally, consisting of standards *a a*, in which the journals of the rollers turn, and shallow boxes *b b*, which serve to receive any material forming 35 weight, by which the rollers are loaded down whenever desired.

These rollers are connected by the following means:

30 D D is a double-armed bearing attached rigidly to frame B' of the rear roller and projecting forward a suitable distance, where it is formed with a circular disk *c*.

E is a circle-plate resting on top of disk *c*, being attached by a bolt *d*, around which it 45 turns freely.

G is an arm connected with the front frame B by means of ears *ff* of the frame, in which turns a spindle *g*, that forms the front end of arm G. This forms a joint at right angles to the length of the rollers, which joint allows 50 both of said rollers to tilt up and down at

either end in passing over irregular surfaces. The opposite end *h* of arm G passes between lugs *ii* of the circle-plate E, and projects over a segment *k* on the fixed bearing D D. At the 55 ends of this segment are pins or lugs *ll*, which form stops to the swinging of arm G in either direction beyond a certain limit.

By the construction above described a universal joint is produced, first, vertically by 60 means of the spindle *g*, resting in the bearings *ff*, which allows the ends of the rollers to rise and fall, and, second, horizontally by means of the circle-plate E turning on the disk *c*, which allows the rollers to turn out of line in passing 65 corners and curves, as indicated by the dotted lines, Fig. 1. It is an objection to ordinary rollers of the kind that in thus turning corners and curves there is no stop to limit the cramping action, and sometimes the turn is so 70 sharp that the rollers will cramp to a right angle, or even more, and frequently disarrange the machine. In this invention the difficulty is obviated by the stops *ll*, which limit the swing of the arm G and stiffen the connection 75 when the parts meet. By this means the rollers cannot cramp beyond a certain angle, which is such as to cause the rear roller to properly follow the front one in passing a corner. In some cases, and especially with 80 heavy rollers, a segment *k* is used in front of the circle-plate E, attached to projections *xx* of the bearing D D, said segment being also provided with stops *ll*, similar to those on the rear segment, and for the same purpose. 85

In straight work it is designed that the rollers shall stand square and run in a direct line. To insure this the following arrangement is used:

m is a notch formed centrally in the inner 90 edge of the rear segment *k*.

n is a slide on arm G, pressed back by a spring *o* toward the segment. This slide has a shank *p*, which passes through a slot *r* of arm G, and has a detent *s*, that engages with 95 the notch *m*. When the parts are so engaged the arm G is locked to the segment *k*, and both rollers stand square and move in a direct line.

t is a rod connected by a suitable joint with the top of slide *n*, thence extended forward 100 and jointed to a crank *u* of a shaft *v*, extending longitudinally of the frame B, resting in

suitable bearings, and having at the opposite end a foot-lever *w*, which is turned at any time by the driver, who presses his foot on it. By so pressing on the treadle the shaft is turned, and the connecting-rod drawn back, the detent freed from the notch in the segment, and in that condition the rollers are free and can be cramped in turning corners.

10 *J* is a spring of any suitable kind, having a knuckle *j*, fastened to arm *G* by a set-screw, said spring extending transversely and bearing on a pin *e* of the frame *B* of the front roller. Said spring tends to hold the roller down and prevent it from tilting when it 15 stands at an incline.

Having described our invention, what we claim as new, and desired to secure by Letters Patent, is—

1. In a land-roller, the combination of the 20 double-armed bearing *D D*, rigidly attached to the frame of the rear roller, the arm *G*, jointed to the frame of the front roller, the circle-plate *E*, attached to said arm and jointed to the bearing *D D*, and the segment *k*, attached to the bearing *D D* and provided with pins or lugs *l l* at its ends, which serve as stops to the side motion of bar *G*, as herein shown and described.

2. In a land-roller, the combination of the 30 double-armed bearing *D D*, rigidly attached to the frame of the rear roller, the arm *G*, jointed to the frame of the front roller, the circle-plate *E*, attached to said arm and jointed to the bearing *D D*, the rear segment *k*, attached to the bearing *D D* and provided with 35

pins or lugs *l l* at its ends, and the front segment *k'*, similarly attached to front projections *x x* of the bearing and provided with pins or lugs *l' l'* at its ends, as shown and described, and for the purpose specified. 40

3. In a land-roller, the combination of the double-armed bearing *D D*, attached to the frame of the rear roller, the arm *G*, jointed to the frame of the front roller, the circle-plate *E*, attached to the arm and jointed to the bearing, the segment *k*, provided with the notch *m*, the slide *n*, provided with the detent *s*, engaging said notch, the spring *o*, bearing against the slide, the shaft *v*, provided with treadle *w*, attached to the frame of the front roller, and the rod *t*, connecting the slide *n* with a crank *u* of shaft *v*, as shown and described, and for the purpose specified. 45 50

4. In a land-roller, the combination of the double-armed bearing *D D*, attached to the rear roller-frame, the arm *G*, jointed to the front roller-frame, the circle-plate *E*, attached to arm *G* and jointed to the bearing *D D*, and the spring *J*, attached to arm *G* and bearing on a pin *e* to prevent tilting of the front roller, 55 60 as herein shown and described.

In witness whereof we have hereunto signed our names in the presence of two subscribing witnesses.

FRANK. G. DODGE.
DANIEL C. STARKS.
